UNITED STATES PATENT OFFICE.

SAMUEL M. McCORD, OF SPRINGFIELD, OHIO.

IMPROVEMENT IN CHIMNEYS.

Specification forming part of Letters Patent No. 117,555, dated August 1, 1871.

To all whom it may concern:

Be it known that I, SAMUEL M. McCORD, of the city of Springfield, in the State of Ohio, have invented a new and useful Improvement in Fire-Proof Chimney-Flues; and I do hereby declare that the following is a full, clear, and exact description thereof, which will enable others skilled in the art to make and use the same, reference being had to the accompanying drawing forming part of this specification.

This invention relates to improvements in fire-proof chimney-flues; and it consists in the application of earthen piping to the interior of said flues, placed one upon the other the entire length of the flues, supported from the base of the lower section, and in such manner as to leave ventilating-spaces between the outer wall B and the inner side of the chimney A, all of which will be more fully described in the specification.

In the drawing, Figure 1 represents a vertical section of a chimney-flue with the piping in position. Fig. 2 is a horizontal section on line *xx*. Fig. 3 represents a section of the piping.

In the drawing, A represents a chimney-flue of the ordinary construction, in the interior of which are arranged the sections of piping B placed one upon the other to the upper end of the flue. They may be of any desirable size and thickness to suit the different sizes of chimney-flues, and may be of any shape preferred.

The object of my invention is to prevent possibility of fire from the cracking of the brick walls of the chimneys of buildings, whereby such great danger arises from fire. The cracks are often also produced by the contraction and expansion of the brick-work, as well as from the settling of the building. By my invention this difficulty is entirely obviated, as the piping, being loosely placed in the flues, is not affected by the settling or cracking of the chimney. The air-spaces C, in the corners of the flue tend to keep the piping cool and add to the draught of the chimney, and serve as ventilators to rooms by apertures *a a*, with or without registers. These apertures may be made at any point in a room, either in the fire-place or the walls of the room.

Having thus described my invention, what I claim, and desire to secure by Letters Patent, is—

The combination of the piping B with a chimney-flue A, ventilator C, and air-ducts *a a*, in the manner and for the purpose herein set forth.

SAMUEL M. McCORD.
